UNITED STATES PATENT OFFICE

MAXWELL T. ZEIGLER, OF HUNTINGTON PARK, CALIFORNIA

APPARATUS FOR AGITATING WATER WHILE FREEZING ICE

Application filed November 7, 1928. Serial No. 317,779.

This invention, in its broad aspect, relates to an improved method and apparatus for freezing water into ice and particularly relates to a method and apparatus for producing an ebullition of the water while it is being cooled and while it is freezing so as to produce clear ice.

Heretofore in freezing ice for commercial purposes it has been customary to discharge air into the water to be frozen through stationary metal tubes producing the desired ebullition required to form clear ice. When stationary metal tubes are employed for this purpose they become frozen fast in the ice and a separate operation known as "needling" is frequently necessary to free the tube from the ice. Also as the water cools and becomes more dense, quite a relatively high air pressure is necessary to produce the desired ebullition or agitation to produce clear ice.

It is one object of this invention to produce a novel method and apparatus for commercially freezing water into ice which employs a movable or flexible tube for discharging the air into the water to be frozen, producing the desired ebullition and at the same time preventing the tube from becoming frozen in the ice, thus eliminating the "needling" and also permitting a lower air pressure to be used but producing substantially equal results to those accomplished where a stationary metal tube is employed.

Another object of the invention is to provide an improved method and apparatus for freezing water into ice wherein the tube through which the air is discharged into the water is continually moved and gradually withdrawn from the water as it freezes.

A further object of the invention is to provide an improved apparatus which is of convenient, simple and durable construction for accomplishing the above mentioned results.

With the foregoing and other objects in view which will be made manifest in the following detailed description and specifically pointed out in the appended claims, reference is had to the accompanying drawings for an

illustrative embodiment of the invention, wherein:

Fig. 1 is a longitudinal vertical section through an ice can illustrating the apparatus and illustrating the ice during its formation. 55

Fig. 2 is a transverse vertical section through the ice can shown in Fig. 1.

Fig. 3 is a partial view in vertical section taken substantially upon line 3-3 upon Fig. 1. 60

Fig. 4 is a partial view in vertical section of the lower end of the flexible conduit employed.

Fig. 5 is a partial view in elevation illustrating one of the drums on which the flexible conduit is adapted to be wound. 65

Referring to the accompanying drawings wherein similar reference characters designate similar parts throughout the invention is illustrated as having been applied to a single ice can 10 which may be one of a plurality or battery of cans disposed within a brine tank 11. It is to be understood, however, that the invention may be applied wherever a liquid is to be frozen into a solid and that the drawing is merely illustrative of the use to which the invention is most applied, namely, commercially freezing water into ice. The ice can 10 and brine tank 11 may be of any conventional construction and disposed thereover is an air header 12 which in the preferred form of construction is a rotatable pipe. This air header is connected to any suitable source of compressed air or a compressed gas such as an air compressor so that air may be supplied therethrough to the various ice cans 10. Over each ice can 10 a drum 13 is mounted having an aperture 15 formed therein to receive a nipple 16 communicating with the interior of the air header 12. A flexible and movable conduit 17 is fastened to the nipple 16 and is suspended therefrom into the ice can 10. This conduit is in the form of a rubber hose which preferably has a short section of metallic tubing 18 thrust into its lower end which keeps the lower end of the tubing open and acts as a weight. 75

The operation is as follows: After the ice cans 10 have been filled with water and posi- 100

tioned in the brine tank 11 the flexible conduits 17 are lowered into their respective ice cans. The lower end of each conduit initially is about 7 or 8 inches from the bottom of the ice can and air is disposed therethrough from the header 12, producing the necessary ebullition of the water to produce clear ice. Usually the lower end of the flexible conduit first tends to arrange itself near a side of the ice can and causing the air to bubble up through the water. The water in the ice can soon begins to become frozen, freezing from the sides of the can inwardly, forming the ice I. This freezing of the ice inwardly leaves the central core of water W to be frozen and as the core of water narrows around the flexible conduit it assumes approximately the shape shown. The restricting of the size of the core restricts the movement of the flexible conduit 17 which as the core becomes smaller vibrates faster and faster and moves about in the core of water. The bottom of the core gradually freezes upwardly and the flexible conduit which is kept agitated or moving by the discharging air kept above it. In most instances it is never absolutely necessary to actually withdraw the conduit 17 from the core of water but as the core gradually freezes upwardly the flexible tube 17 will of itself be moved upwardly and when the complete cake of ice is frozen the tube will be found coiled or resting on the top of the cake without having become frozen in the cake. By rotating the header 12 during the freezing the various drums 13 will be rotated and will wind up the slack in the suspended tubes 17 or if desired the drums may be caused to wind up the tubes 17 gradually if it is thought that there is any danger of the tubes becoming frozen in the ice. As previously explained however, this is not necessary ordinarily as the tube takes care of itself during the flexing and when the complete cake is frozen it will position itself on the top of the cake.

From the above described method and apparatus it will be appreciated that no solid stationary tubes are employed for discharging the air through the water W and consequently no "needling" operation is necessary to free the tube from the ice. Furthermore, a uniform cake of ice is produced which is perfectly clear from top to bottom without the white "bloom" which is usually present in the bottom of the cake where the so-called "high pressure system" is employed. Also, it is possible to use a much lower air pressure in the improved method and apparatus than in most systems due to the fact that the tube is withdrawn from the water ahead of the ice and as the core is being frozen a greater agitation takes place in the water still remaining to freeze. Carbonates and the like which may be in the water of the core are kept thoroughly agitated by the moving

air discharging conduit 17 until they become too heavy to be lifted by the circulation of the water then they settle to the bottom of the core W and are frozen in the ice.

Various changes may be made in the details of construction and in the carrying out of the method within the scope of the invention as defined by the appended claims.

I claim:

1. An apparatus for freezing water into ice, having a container in which the water is adapted to be frozen, a flexible rubber conduit suspended in the container, a metal tube inserted in the lower end of said conduit and completely inclosed therein, and means for discharging air through said conduit.
2. An apparatus for freezing water into ice having a container in which the water is adapted to be frozen, a flexible conduit extending into the container, said conduit having its lower end weighted and having all surfaces capable of coming in contact with the ice formed of non-metallic material, and means for discharging air through said conduit into the container.

In testimony whereof I have signed my name to this specification.

MAXWELL T. ZEIGLER.
